UNITED STATES PATENT OFFICE.

WILLIAM H. DANA, OF DAYTON, OHIO, ASSIGNOR TO LEOPOLD RAUH, OF DAYTON, OHIO.

VOTING-MACHINE.

1,108,491.

Specification of Letters Patent. Patented Aug. 25, 1914.

Application filed February 19, 1912. Serial No. 678,503.

To all whom it may concern:

Be it known that I, WILLIAM H. DANA, a citizen of the United States, and a resident of the city of Dayton, in the county of Montgomery and State of Ohio, have invented certain new and useful Improvements in Voting-Machines, of which the following is a full, clear, and exact description, reference being had to the accompanying drawings, 10 forming part of this specification.

My invention relates to certain improvements in voting machines of the horizontal type, in which the voting levers for the various tickets of the several parties at any 15 election are arranged in horizontal rows, with the offices arranged in vertical rows, and the object of the present invention is to improve the construction and operation of the individual and straight ticket voting devices, and the means for preventing the operation of more than a predetermined number 20 of voting levers in any selected row.

My invention consists of the novel construction and arrangement of parts to be 25 hereinafter particularly pointed out and claimed whereby these results are attained.

In the drawings, Figure 1 is a front elevation of a portion of my improved voting machine, showing a portion of the voting levers and key plates. Fig. 2 is a similar 30 front elevation, with parts of the key plates broken away. Fig. 3 is a vertical cross section, taken on the lines 3, 3, of Fig. 2. Fig. 4 is a horizontal section, taken on the lines 35 4, 4, of Fig. 2. Fig. 5 is a horizontal section, taken on the lines 5, 5, of Fig. 6, and Fig. 6 is a rear elevation of a portion of the machine 40 showing the interlocking devices arranged to conform to the position of the voting levers illustrated in Fig. 1. Fig. 7 is a transverse vertical section, taken on the lines 7, 7, of Fig. 6. Figs. 8 and 9 are rear elevations of a portion of the machine showing the interlocking devices as arranged for 45 primary voting. Figs. 10 and 11 are detail transverse sections, taken on the lines 11, 11, of Fig. 2, showing a straight ticket voting lever, with the coiled spring omitted in Fig. 2. Fig. 12 is a plan view of one of the 50 straight ticket voting bars. Figs. 13, 14 and 15 are details of the straight ticket voting lever constructions. Figs. 16, 17, 18, 19, 20, 21, 22, 23 and 24 are details of the individual voting lever construction, as illustrated assembled in Fig. 3. Figs. 25, 26, 27,

28, 29, 30, 31 and 32 are detail perspective views of the primary interlocking device, showing the various parts and method of assembling the same.

The operating parts of the voting machine are inclosed in the usual rectangular case, made of light framework and supported at a proper height from the ground by suitable standards. As my invention relates to details of construction, I have not thought it necessary to illustrate the complete voting machine. Running from top to bottom of this framework vertically, and a proper distance apart to form the division between the office rows, are a series of guide bars 19, provided with side grooves 18, for the reception of the slideable plates which form the primary interlocking devices of my construction. Riveted to these guide bars and extending horizontally across the framework are a series of Z-bars 35, which divide the framework into horizontal spaces of sufficient width to receive the voting lever constructions for the party rows. Upon these Z-bars, the front key plates of the machine are secured, which consist of plates 150, one for each party row, fitted closely together to form the front plate construction of the machine, and in these plates the voting levers are mounted. The front face 55 of each key plate is furnished with a plate or metal strip 2, to form a division between the party rows, and upon each of these plates is riveted a guide plate 3 to provide a guide for the finger in voting the various key 60 levers.

The individual voting levers and their various parts are separately illustrated in Figs. 18 to 24 inclusive. These individual levers are all constructed in the same way, 65 and comprise the actuating lever arm 6, which is mounted on shaft 8, which has its bearing in a suitable opening in the key plate. The shaft 8 inside the key plate carries an arm 9 with a sleeve 10 projecting 70 inwardly parallel to the shaft 8, and this sleeve 10 carries a screw 11 which may be advanced or retracted. An opening 60 Figs. 16 and 17 is formed in the key plate in line with this screw when it is in normal position, so that in order to lock the key levers 75 out of operation, the screw can be turned until the head 75 projects into the opening in the key plate, as shown in Fig. 16. The screw can also be adjusted so that the head 80

of the screw will clear the opening in the key plate while at the same time the inner end of the screw will clear the openings 151 in the straight ticket bar 13, which is 5 mounted for lateral adjustment by a pin and slot connection with the framework, and is arranged to be actuated by the straight ticket lever, as hereinafter described, to actuate all of the individual 10 voting levers in any particular party row. But where there is any provision of the law that a straight ticket cannot be voted for any particular office, then these screws are adjusted so that the individual levers will 15 not be actuated by the straight ticket bar.

Mounted on the shaft 8, inside the arm 9 of the individual ticket lever is a plate, shown separately in Fig. 23 and shown mounted in Fig. 20. This plate carries a 20 pin 40, which makes connection with the counting mechanism for registering the vote, and which also actuates the interlocking mechanism to prevent more than a pre-determined number of voting levers being 25 actuated in any particular row. The lower end of the back portion 12 of this plate is normally held in engagement with the sleeve 10 by the coiled spring 14, one end of which bears on the upper edge of the back portion 30 of the plate and the other end engages the sleeve 10. It will be evident from this construction that the pin 40 in its movement will have a resilient connection with the voting lever so that as hereinafter described, 35 any undue strain on the voting levers cannot be brought to bear on the interlocking devices which are in contact with the pins 40.

Each horizontal row of voting levers is provided with a straight ticket bar 13, 40 formed with recesses on its upper edge, but leaving the contact shoulders 53, one for each ticket lever, and the screws 11 of each individual lever normally project in front of these shoulders 53. Each of these bars 45 is held in position by suitable screws taking through slots 15 in the bar, and at one end each straight ticket bar has an upwardly projecting arm 54 which is contacted with and actuated by its respective straight ticket 50 lever, so that with the movement of the straight ticket lever all of the individual levers in the particular party row will be actuated. These straight ticket levers are of the same general construction as the 55 individual levers comprising an arm 56, mounted on a shaft 16 and carrying arms 20 and 116. The arm 20 carries the screw 21, the head of which is arranged to be projected through an opening 22 Fig. 10 in 60 the key plate corresponding to the opening 60 for the individual levers, so that the straight ticket lever can be locked from movement by bringing the head of the screw into this opening. The other arm 116 is 65 arranged to contact with the upwardly pro-

jecting arm 54 on its particular straight ticket bar. The contacting surface of this arm is formed of very short curvature near the axis of the lever, and of long curvature as the distance increases from the center. 70 The effect of this construction is illustrated in the three positions of the straight ticket lever as shown in Fig. 2, and marked A, B and C. In the position of the straight ticket lever marked A in Fig. 2, we have the lever 75 in its normal position. The position of the lever marked C in Fig. 2 shows the lever actuated half its stroke, and it will be seen that the contacting point of the arm 54 on the straight ticket bar with the lever arm 116 is only slightly farther from the axis of the lever than at the commencement of the stroke, while in the last position of the straight ticket lever marked B in Fig. 2, the 80 point of contact is near the outer end of the 85 arm 116. With this construction, it will be seen that the greatest amount of leverage is obtained at the beginning of the stroke of the straight ticket lever, as it should be, because it then has to start the movement of 90 the key levers and their interlocking devices, and that the leverage decreases during the last half stroke, inasmuch as the force required to complete the movement is very much less than that required in the start. 95

The primary interlocking devices which are employed to prevent the operation of more than the desired number of voting levers are illustrated in their several parts and as assembled in Figs. 25 to 32 inclusive. 100 Each interlocking device, of which there is one for each individual key lever, is made up of a plate 23, provided with a transverse groove 24 at its upper end and a block 25 having a beveled surface 26 at its lower end. The plate 23 carries at its upper end the laterally slidable plate 27 with a vertical slot 28 therein, with its upper edge cut away and beveled at 29 to engage the beveled surface 26 on the interlocking device 110 immediately above it. The plate 27 is provided with a tongue 30 which fits in the groove 24 of the plate 23, and a pin 31 on the plate 23 in the groove projects into the cut-out portion 32 of the tongue 30, so that 115 when the two plates are fitted together, as shown in Fig. 28, the upper plate 27 will have a lateral movement from side to side on the plate 23. To hold the parts in position, I provide the cover plate 33 which is 120 riveted on the plate 23 through the rivet openings 34. These devices comprising the fixed plate and the laterally movable plate comprise the primary interlocking devices, of which there is one for each individual 125 key lever, and these interlocking devices are mounted in each vertical row in the grooves 18 of the guide bars 19. As mounted in normal position, the beveled surface 26 at 130 the lower end of one device engages with

the beveled surface 29 on the upper edge of the movable plate of the device next below it, and it will be evident that as any movable plate 27 is shifted laterally, the beveled surfaces will pass each other, and the interlocking devices will be separated the distance between the contacting surfaces at each side of the beveled portion. The normal position of these primary interlocking devices 5 is illustrated in the vertical column marked A²⁹ in Fig. 6, while the other position is indicated in the columns marked A²⁸ and A³⁰ in said Fig. 6. This space or movement of the interlocking devices I designate as 10 15 the unit space or unit movement.

The uppermost interlocking device for each office row is not provided with the sliding plate 27, but there is substituted therefor the device illustrated in Fig. 30. 20 This device comprises a plate 39, formed with side grooves 36, cut away at 37 at its rear portion, carrying a plate 38 which is provided with a flange 42 at its upper edge carrying a contact plate 43. The plates 38 25 and 39 are drilled with a series of holes indicated in Fig. 30 by the letters and numerals 0, 1, 2, 3, 4, 5, 6, R and L. These holes are designed to receive the pin 44, which is passed through the plate and rests 30 on the upper edge of the uppermost plate 33, as shown in Fig. 7.

The contact plates 43 bear upon the pins 45 of the respective cam plates 46 which are mounted with their hubs 47 in a horizontal groove in the cam plate holder 48 which is secured horizontally to the framework across the upper end of the rows of primary interlocking plates. The hubs 47 of these cam plates 46 bear against the 40 curved surface 49 of the next adjacent plate, and the cam plates are pivotally mounted by pins 50 inserted through the hubs of the cam plates and the plate holder, and when so pivoted, the cam plates are 45 designed to allow the movement of the primary interlocking plates a single unit space, but for the purpose of grouping together any desired number of primary interlocking devices of selected office rows, these 50 pivot pins 50 can be withdrawn and inserted in holes 51 Fig. 9 in the plate holders designed to carry them, and in this event the construction of the cam plates is such that the particular cam plate which is free to 55 move laterally will allow a movement of two unit spaces in the particular office row of primary interlocking devices which it controls. This construction for the grouping together of office rows forms no part of my 60 present invention and need not be further described.

The advantages derived from my novel construction and the operation of the several parts can be better understood by a description of the method of preparing the 65

ballots and voting levers for an election. In the first place, I slide into the grooves 52, Fig. 7, a printed strip with the titles of the offices that are to be voted on, generally called the head of the ticket, so that the vertical lines of the strip register with the vertical lines of the metal strip 151 as shown in Fig. 1. In like manner, I mount the several ballot strips for the various party nominees,—as illustrated, a Republican ballot strip in the next space beneath the head of the ticket strip. Then the screws 11 carried by the voting levers are adjusted for any vertical column containing a list of officers for which office the elector is required by law to vote separately therefor,—for example, in the column marked 30 for Board of Education in Fig. 1, this adjustment is made to withdraw the screws of these particular voting levers from contact with the shoulders on the straight ticket voting bar 13. Also for any party columns that are not to be used, or for locking all the party levers when the machine is being set up for a primary election, the screws are adjusted so 70 75 80 85 as to lock the voting levers to the key plate. I then insert the Democratic ballot strips which cover up the holes 60, and for any space for which there is no candidate, I lock the voting lever to the key plate by its 90 95 screw 11.

In Fig. 2 the uppermost of the individual voting levers on the left is shown in its normal or unvoted position, with the spring 14 and the plate 81 mounted on the shaft 8, 100 and the lower end of the plate being pressed firmly against the arm 10 of the voting lever. The pin 40 of the voting lever as shown in Fig. 3 is then projected through the slot 28 of the movable member 27 of its 105 primary interlocking device, so that the movement of the voting lever into voted position, as shown in Fig. 2 on the right in column A, will cause the movable plate 27 of the interlocking device to shift laterally, 110 as shown in Fig. 6 in the interlocking device marked B²⁸. In this same Fig. 6, the plate marked B²⁹ shows the interlocking device in its normal position.

In the position of the primary interfering 115 plate marked B³⁰ in Fig. 6, the key lever has only been moved one half of its full movement, yet it will be seen that the plate 27 with the half movement has raised the interfering plate above it the unit space, 120 and it is, therefore, the first half movement of the voting lever which shifts the interfering plates.

The raising of the primary interlocking devices by the movement of any individual 125 voting lever raises the uppermost plate by contact with the pin 44, which for normal operation is placed in the hole marked 1 on this plate. These holes in the plates 38 are arranged for the amount of unit space I 130

have provided, each one-sixteenth of an inch higher than the hole below it. Hole 2 is one-sixteenth of an inch higher than hole 1, and hole 3 one-sixteenth of an inch higher than hole 2, and so on, and the distance between said holes is identical with the unit space provided for the separation of the interfering plates. The holes marked R and L, however, are only a very slight fraction of an inch respectively higher and lower than the hole 1,—say .005 of an inch. The reason for this will be later explained.

For voting any columns in which only one candidate is to be selected, the secondary interfering plate 46 for that row is retained pivoted in the holder, and this plate can only move a sufficient space to allow one unit space to be taken up in said row. Where, for example, there are candidates for the office of coroner, as illustrated in columns 28 and 29, of Fig. 1, and two candidates are to be selected, the cam plate 46 of one of these rows is released by the pivot pin being withdrawn, so that the two rows are grouped together, and two candidates can be voted for in a single row or in the separate rows.

Ordinarily where provision is made for coupling together various selected rows for multicandidate group voting, it is necessary to provide as many separate rows as there are candidates; but let us assume with my construction that we have two office rows and three candidates are to be selected. In this event, by reason of my construction in which the various holes are provided a unit space apart in the plates 38 which receive the pins 44, I am able to extend, so to speak, the space movement of the primary interlocking devices, and by placing the pin 44 in the hole marked 2 in one of the rows and coupling the two rows together by removing the pivot pin for the particular interlocking cam plate for that row, I can obtain three spaces for voting in either of the rows. Therefore by making both adjustments through the pins 44 in the desired hole in the plate 38 and through the interlocking cam plates for the several office rows, I am able to provide for multicandidate group voting in very much less space than is ordinarily required.

Now as to the use of the holes marked R and L in the plate 38,—suppose after coupling together a number of rows for a considerable group, say of seven candidates, upon operating the seven levers, I find that the seventh key lever does not operate as easily as the other six. This would indicate that there was not sufficient space between the bearing surfaces to allow properly for the necessary movement. I would then remove one of the pins 44 from the normal hole 1 and place it in the hole marked L, which would give me .005 of an inch more

space between the bearing surfaces. Where I had a group of fifteen or twenty office rows, it might be necessary to shift two or three of the pins 44 into the holes marked L in the event that the last keys voted were difficult to operate.

In the event that after voting the allowed number of keys in any particular group, I found that I could partially vote another key, one or more of the pins would be removed from the normal hole marked 1 and placed in the hole marked R, which would give to the extent of .005 of an inch less than the full unit space movement in that particular row. In this way, I would take up the surplus space. By this arrangement, having arranged any group of office rows for multicandidate group voting, upon a trial I can readily either take up or increase the space so that accuracy of movement of the required number of voting levers may be obtained.

The resilient connection between each individual voting lever and the pins 40 for actuating the counting mechanism is of importance if an elector has voted for certain individual names in one party row, and then should operate the straight ticket lever in another party row. In this event, the straight ticket bar for such party row will actuate all of the key levers, but the pins 40 of the key levers in the office row that has already been voted will be held by the interlocking devices in unvoted position, and the springs 14 will yield, and when the party lever and the straight ticket bar are returned to normal by the spring 70 mounted on the stud 71, (Fig. 2) and bearing between the stud 72 and the actuating arm 54, the spring 14 will return the particular individual lever back to its normal position; whereas, without the resilient connection for the individual lever, undue strain would have been exerted on said lever by means of the compound leverage of the party lever.

In order to prevent any elector from forcing any of the individual levers too far to the right when voted for separately, I provide studs 73 on the inner surface of the key plate 150, as shown in Fig. 3, to serve as stops. Moreover, in multicandidate voting, when the elector votes the levers for a group separately, and there is a large group, say fifteen or more, he can continue to vote said levers, until the last lever operated automatically returns to normal, because the proper number of levers have been operated, and the next one operated merely places its spring 14 under tension. With the ordinary construction, if the last two or three voting levers he is permitted to operate should require more pressure than normal, owing to the increase in friction, the elector cannot tell whether he has voted the correct number unless he count the levers he has operated.

To hold the various primary interlocking devices under proper tension, each of the devices 39 Fig. 7 is provided with a pin 76, and between this pin and a stud 77 on the inner 5 surface of the key plate, a coiled spring 73 bears, the various springs 78 being mounted on screw studs 79, secured in the upper end of the guide bars 19.

Having thus described my invention, what 10 I claim as new and desire to secure by Letters Patent, is:—

1. In a voting machine, the combination of a series of key plates, one for each party row, running horizontally across the machine, a series of transverse guide bars, said bars having grooves, a series of interlocking plates, one series for each office row mounted in said grooves, each key plate having a web near its upper edge, a party lever, 15 and a series of individual voting levers rotatably mounted beneath said web, one for each office row, with means intermediate the individual voting levers and the interfering plates to resiliently actuate the same, as 20 and fore the purpose set forth.

2. In a voting machine, the combination of straight ticket voting levers rotatably mounted, one for each party row, each lever having an arm carrying a screw, also another arm having an elongated radial bearing surface and a slidable and automatically returnable bar, with which said latter arm engages, said bar having a series of transverse bearing surfaces, as and for the purposes set forth.

3. In a voting machine, the combination of a straight ticket bar, with bearing surfaces thereon, a series of voting levers rotatably mounted and arranged in party and 40 office rows, each lever having an arm carrying a screw pin, said pin normally to be engaged by its respective bearing surface of the straight ticket bar, whenever the said bar is being operated, by means of its respective party lever and adapted to be withdrawn from said bearing surface, as and for the purpose set forth.

4. In a voting machine, the combination with a series of interlocking plates, of a 50 series of voting levers, rotatably mounted, arranged in party and office rows, said levers having a shaft, with a spring-pressed plate mounted thereon, said plate carrying an actuating pin to engage with and resili-

ently actuate its respective interlocking 55 plate, whenever the said lever is operated, as and for the purpose set forth.

5. In a voting machine, the combination of a straight ticket voting bar, and a series of voting levers, rotatably mounted, in party 60 and office rows, said levers having a shaft, with a spring-pressed plate carrying an actuating pin mounted therein, the said shaft having an arm carrying a screw pin capable of being adjusted for engagement or disengagement with the said bar, as and for the purpose set forth.

6. In a voting machine, the combination of a series of voting levers, rotatably mounted, in party and office rows, said levers having a shaft, with a spring-pressed plate, mounted thereon and carrying an actuating pin, the said shaft having an arm carrying a screw pin, said pin being capable of being adjusted, so as to enter a hole or 70 aperture in the front wall or key plate for the purpose of locking its respective lever against movement.

7. In a voting machine, the combination with a series of interlocking plates, of a 80 series of voting levers, rotatably mounted, in party and office rows, with an actuating pin on each lever to engage its respective interlocking plate, a series of vertical bars, having longitudinal grooves, and a series of bifurcated rectangular plates slidably mounted therein, said plates having near their lower end a rectangular abutting surface beveled at one end, and a transverse movable member secured to its upper end, said member 90 having a longitudinal slot, through which extends the actuating pin of its respective voting lever, the upper end of the said movable member having a beveled offset near the center of its rectangular abutting surface, normally meshing with the rectangular and beveled surface of the plate above it, and to cause all the said plates to move upward one unit space whenever the said movable member is shifted from its normal 95 100 to a voted position by means of its respective voting lever, as and for the purpose specified.

WILLIAM H. DANA.
